UNITED STATES PATENT OFFICE.

JOHN M. STUDEBAKER, OF SOUTH BEND, INDIANA.

DESIGN FOR A COLLAR FOR AXLE-SKEINS.

SPECIFICATION forming part of Design No. 26,223, dated October 27, 1896.

Application filed April 25, 1896. Serial No. 589,128. Term of patent 14 years.

To all whom it may concern:

Be it known that I, JOHN M. STUDEBAKER, a citizen of the United States, residing at South Bend, in the county of St. Joseph and State of Indiana, have invented and produced a new and original Design for Collars for Axle-Skeins, of which the following is a specification, reference being had to the accompanying drawings, forming part of this specification, by letters of reference marked thereon, in which—

Figure 1 is a perspective view of the collar. Fig. 2 is a longitudinal section through the collar, and Fig. 3 an end view thereof.

The design consists in the form of the collar as shown in the drawings.

The collar is annular and has a central ex-

terior circumferential rib A and annular flanges B C on opposite sides thereof, and the flange C has a segmental extension c on its lower edge.

The essential feature of the design is the rearward segmental extension c.

What I claim is—

The design for collars for axle-skeins as hereinbefore set forth.

In testimony that I claim the foregoing as my own I affix my signature in presence of two witnesses.

JOHN M. STUDEBAKER.

In presence of—

JAMES DU SHANE,
GRACE C. ECCLESTON.
